Sethy Hunter.

Letters Patent, issued Feb. 1828.

The substance referred to in these Letters Patent, and making part of the same, containing a description in the words of the said Sethy Hunter, himself, of his improvement in making teeth - metallic teeth.

All this improvement, is in small or two small pieces of platinum, which is inserted into the teeth at the moment of their fabrication which much weakened the teeth, and very often causes them to split in the taking or in the soldering and more often comes out or separated itself from the teeth when in use, all these great disadvantages are obviated by not inserting any platinum into the teeth at the moment of their fabrication, and instead of it, to make with a small wire a hole through the teeth, which after the baking is stopped or filled with silver, gold or platinum wire and gold solder melted on both extremities of it, the solder must to the strength of the teeth and they are lighter by not using platinum. teeth made so of a good material, are will break no separate themselves from the hold, nor the hold from the platinum which brings the art of dentistry to the perfection you will see in teeth. Then do we be aware to myself the unauthorized, without a sensible society from this improvement to be ignorant, the common practice of infringing patent rights, I will specify, that porcelain teeth may be well secured to a plate, if the small hole is made to the teeth, without passing entirely through, and a wire of silver or gold, after the baking is introduced into the hole and gold solder melted into it, which makes a perfect hold, if at the time of the fabrication of the teeth, the said hole we made a little larger at the bottom than at the top, this made would be still weaker, but perhaps not as strong as the other.

X5058

allowing that these important improvements have been suggested to me, by necessity which is truly the mother of invention; Blawie being at this time so dear, so scarce, & in fact, not being able to obtain any, I have made the experiments ~~it~~ have made both without, it is ~~to~~ to settle whether them to a galat plat, that I have no doubt that experience will prove that this new mode has a great, superiority over the ancient, modes.
